[57] CLAIM

The ornamental design for an umbrella dome stadium, as shown and described.

DESCRIPTION

FIG. 1 is a plan view of the design of the present invention;

FIG. 2 is a side elevation of the design of the present invention;

FIG. 3 is a cross-sectional view taken along line 3—3 of FIG. 2, the broken line showing of a playing field is for illustrative purposes only and form no part of claimed design; and,

FIG. 4 is a cross-sectional elevation along line 4—4 of FIG. 2.

All four sides of the stadium are identical to the view shown in FIG. 2.

FIG. 1

FIG. 2

FIG. 3

FIG. 4
